CLAIM

I claim the ornamental design for a combined travel digital alarm clock and picture frame, as shown and described.

DESCRIPTION

FIG. 1 is a perspective view of a combined travel digital alarm clock and picture frame shown in a partially open position.

FIG. 2 is a front elevation of the combined travel digital alarm clock and picture frame shown in a fully open position.

FIG. 3 is a front view of the combined travel digital alarm clock and picture frame shown in a closed position.

FIG. 4 is a rear view of the combined travel digital alarm clock and picture frame shown in the fully open position.

FIG. 5 is a rear view of the combined travel digital alarm clock and picture frame shown in a closed position.

FIG. 6 is a top plan view of the combined travel digital alarm clock and picture frame shown in a fully open position.

FIG. 7 is a top plan view of the combined travel digital alarm clock and picture frame shown in a closed position.

FIG. 8 is a bottom plan view of the combined travel digital alarm clock and picture frame shown in a fully open position.

FIG. 9 is a bottom plan view of the combined travel digital alarm clock and picture frame shown in a closed position.

FIG. 10 is a right-side view of the combined travel digital alarm clock and picture frame shown in a closed position; and,

FIG. 11 is a left-side view of the combined travel digital alarm clock and picture frame shown in a closed position.

The broken lines in the drawings are used to show portions of the combined travel digital alarm clock and picture frame that do not form part of the claimed design.
